(57) **CLAIM**

The ornamental design for an air curtain merchandiser with flat front, as shown and described.

DESCRIPTION

FIG. 1 is a perspective view of a merchandiser showing my new design;

FIG. 2 is a front elevational view of FIG. 1;

FIG. 3 is a top view of FIG. 1;

FIG. 4 is a left side elevational view of FIG. 1;

FIG. 5 is a right side elevational view of FIG. 1;

FIG. 6 is a rear elevational view of FIG. 1;

FIG. 7 is a bottom plan view of FIG. 1;

FIG. 8 is a perspective view of an alternate embodiment of that shown in FIG. 1: the broken line showing is for illustrative purposes only and forms no part of the design; and,

FIG. 9 is a front elevational view of FIG. 8; the top, side, rear and bottom views of the alternate embodiment shown in FIGS. 8 and 9 are identical to the top, bottom, rear and side views of the first embodiment, as shown in FIGS. 3, 4, 5, 6, and 7 respectively.
